UNITED STATES PATENT OFFICE.

CARLOS E. SAMPSON AND WALTER WOODS, OF ALAMEDA, CALIFORNIA.

CRUDE-OIL STILL.

1,177,816.

Specification of Letters Patent.

Patented Apr. 4, 1916.

Application filed February 16, 1915. Serial No. 8,564.

To all whom it may concern:

Be it known that we, CARLOS E. SAMPSON and WALTER Woods, citizens of the United States, residing at Alameda, in the county 5 of Alameda and State of California, have invented new and useful Improvements in Crude-Oil Stills, of which the following is a specification.

This invention relates to crude oil stills 10 and it consists in the novel features herein-after described and claimed.

An object of the invention is to provide a still of simple structure adapted when in operation to efficiently and quickly convert 15 crude oil into vapor or gas whereby the solid matter or residuum may be easily separated from the same.

With the above objects in view the still includes a walled structure having heat inlet 20 and heat outlet openings. Headers are supported in the walls of the structure and are connected by pipes which are arranged in inclined positions. The said pipes are arranged in sets and partitions are located between the sets and constitute baffle walls for 25 the purpose of properly directing the heated gases along the pipes as it passes along the same. Means is provided for admitting crude oil into the lowermost header and 30 means is provided for permitting the vapor and residuum to escape from the uppermost header of the series of headers.

In the drawings:—Figure 1 is a vertical longitudinal sectional view of the still. 35 Fig. 2 is an enlarged detail sectional view through one of the headers of the still. Fig. 3 is a side elevational view of one of the headers.

The still comprises a wall structure 1 having headers 11 located in the opposite walls thereof. A pipe 3 is connected with the uppermost header 11 and a pipe 4 is connected with the lowermost header of the series of headers. 45

The structure 1 is provided in one of its walls with a heat inlet opening 9 through which heated gases may be introduced into the said structure and the structure is further provided at its top with an outlet opening 10. As hereinbefore stated the headers 50 11 are mounted in the opposite walls of the structure 1. The headers at one of the walls occurring opposite the closed portions of the opposite wall and vice versa are best shown 55 in Fig. 1 of the drawing. Some of the headers 11 are inwardly disposed at their

intermediate portions as at 2 whereby the inner surfaces of the said headers lie in planes at an angle to each other. These angularly disposed surfaces of the headers at 60 one side wall of the structure are parallel with portions of the inner surfaces of the headers at the opposite side of the structure. Pipes 12 connect the headers at the opposite sides of the structure 1 together. 65 These pipes are arranged in inclined positions as shown in Fig. 1 of the drawing and communicate with the headers at the opposite walls of the structure at their opposite ends at the inner surfaces of the headers 70 which are parallel with respect to each other. The pipes 12 of each set of pipes are parallel and each set of pipes is inclined in an opposite direction from the next adjacent set of pipes. 75

As will be seen in Fig. 2 of the drawing each of the intermediate headers 11 comprises two angularly disposed sections which join with each other and one set of pipes 12 connects with one section while the adjacent 80 set of pipes 12 connects with the other section of the header.

Partitions 13 of fire brick or other suitable material are located over each set of pipes 13 and constitute baffle walls which cause the 85 heated gases entering through the opening 9 to pass in a zigzag path through the still. Consequently the oil which is in the pipes 12 is subjected to a blast of heated gas and this has the effect of separating the vapor in the 90 oil from the heavier particles.

The crude oil is led into the lowermost header 11 through the pipe 4 and the said oil passes up through the pipes 12 and enters all of the other headers 11 in the structure 95 1. During the upward movement of the oil the lighter particles thereof are vaporized. The vaporized oil and the residuum is taken from the still through the pipe 3. After the vaporized oil and the heavier particles have 100 been conducted from the still they are separated from each other in any suitable manner by passing the said materials through a separator and finally condensing the vaporized oil into liquid form. Therefore it will 105 be seen that a still of simple structure is provided and that when in operation the heavier particles of oil as they are passed through the still are subjected to the most intense heat and consequently the process of converting the oil into vapor is materially facilitated. 110

Having described the invention what is claimed is:—

A still comprising a walled inclosure having a heat inlet and a heat outlet, headers located in the walls of the inclosure, pipes connecting the headers at the opposite sides of the inclosure together, said pipes being arranged in sets the pipes of one set being inclined at an angle with relation to the pipes of the next adjacent sets, baffle walls located upon the uppermost pipes of the sets of pipes and dividing the inclosure into heating chambers superimposed one above the other, the adjacent baffle walls converging toward each other whereby the said heating chambers are rendered smaller at one end than at the other, there being spaces provided between the ends of the baffle walls and the walls of the inclosure at the upper

sides of the said heating chambers and at 20 the smaller ends thereof whereby the heat may ascend from the smaller end of one chamber into the larger end of the chamber next above, the admission ends of the said chambers being of greater transverse sectional area than the exit ends thereof, means 25 for admitting crude oil into the lowermost header and means for leading oil and vapor from the uppermost header of the series of headers.

In testimony whereof we affix our signatures in presence of two witnesses.

CARLOS E. SAMPSON.
WALTER WOODS.
